(57) CLAIM

The ornamental design for a wine glass holder, as shown and described.

DESCRIPTION

FIG. 1 is a front, right, and top perspective view of a wine glass holder, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a perspective view of the wine glass holder of FIG. 1 wherein a cup holder and a disc generating part shown separately.

The broken lines shown in the drawings are included for the purpose of illustrating portions of the wine glass holder that form no part of the claimed design.
